UNITED STATES PATENT OFFICE

1,974,001

BOILER

Dominick F. Vallero, Denver, Colo.

Application February 8, 1932, Serial No. 591,515

8 Claims. (Cl. 122—2)

This invention relates to steam-boilers and its primary object is to provide a boiler structure in which simplicity of construction is combined with more than ordinary strength and with great steam-generating capacity.

A further object is to provide a boiler structure in which a succession of large flues takes the place of the usual tubes of tubular boilers, and in which flues having curvilinear surfaces, minimize the deposit of scale and render the use of stay-bolts unnecessary.

Another object of the invention is to provide a boiler structure in which there is a large heat transfer surface, making it readily adaptable to heating and cooling liquids or gases.

Another object resides in the provision of a boiler structure having a plurality of openings affording ready access to the flues for cleaning purposes; a further object is to combine with a steam-boiler, an incinerator for the combustion of trash and garbage; and still other objects may be found in details of construction hereinafter to be described with reference to the accompanying drawings.

In the drawings in the several views of which like parts are similarly designated,

Figure 1 is a perspective view of the boiler,

Figure 2, an end-view of the boiler shown in Figure 1, with the doors removed,

Figure 3, an enlarged fragmentary section showing the connection of the water jackets around the flues through which the products of combustion pass from the combustion chamber to the smoke-outlet of the boiler,

Figure 4, a partially sectional end-elevation of the boiler, the section being taken on the plane indicated by the line 4—4, Figure 1,

Figure 5, a longitudinal section on the line 5—5,

Figure 4, and

Figure 6, an enlarged section showing the dome or steam-space of the boiler.

The boiler, as shown, is composed of two cylindrical sections 5 and 6 connected by an interposed segmental section 7.

The lower section, 5, has an annular water jacket 8 around a space 9 which constitutes the combustion chamber of the boiler, the upper section has a similar water jacket 10 enlarged at the upper portion of the section to provide a dome or steam space 12, and the middle section has a segmental water jacket 13 which at its ends connects with the water jacket of the lower section, as at 14, and which connects with the jacket of the upper section at its points of intersection 15 with said jacket as indicated at 15.

The jackets of the upper and lower sections are furthermore connected by a lengthwise extending hollow neck 16, and the jacket of the middle section connects with the steam space 12 by a similar neck 17. The portions of the jackets connected with the necks are perforated as best shown in Figure 5. The jackets and their connections terminate at distances from the front and rear walls of the structure as at 18 and 19, to provide for the intercommunications of the spaces 60 inside the jackets which constitute heating flues 20, 21 and 22, through which the heat and products of combustion pass from the combustion chamber 9, to a smoke box 23, in the upper section. A pipe 24 connected with the smoke box, 70 extends through the steam space, for its connection with a stack or other draft-inducing element.

The combustion space of the boiler is divided by a bridge 25 into the main combustion chamber 26 having a grate 27 and a smaller auxiliary combustion chamber 28 having a grate 29. The last mentioned chamber is utilized as an incinerator for burning trash, garbage and other refuse matter.

The body of the boiler as described, has at its 80 ends, front- and rear-plates 30 and 31 provided with openings that register with the several flues. Doors 32 and 33 hinged on the plates, normally close the openings and afford ready access to the flues for cleaning or other purposes. A 85 chute 34 closed by a flap-door 35 gives access to the incinerator.

Doors 36 and 37 may be opened or closed to regulate the draft, and doors 38 give access to the main combustion chamber for the supply of 90 fuel to the grate 27. It will be apparent that oil or gas burners may, if so desired, be substituted for the grates.

Water is supplied to the interconnected water jackets through an inlet 39 in the bottom-portion 95 of the jacket of the lower section, and the generated steam escapes from the steam-space through an opening 40 in the top of the upper section. Small openings 50 at the rear end of the boiler, are provided for the purpose of cleaning the water 100 jackets, if desired.

The operation of the boiler will be readily understood. The heating-flues provides a zig-zag course for heat and products of combustion, within the comparatively narrow jackets which 105 constitute the water-space of the boiler. The boiler thus has an unusually large expanse of surface for heat-interchange, and steam is rapidly generated with the minimum expenditure of fuel.

Inasmuch as the surfaces of the flues are curved, no stay-bolts are required and scale formed upon the surfaces will fall to the bottom of the flues to be removed through the openings at the ends of the flues. The water supplied through the inlet rises transverse to the course of the heat and smoke through the flues, and every part of the structure is accessible from outside the boiler by the provision of the several doors.

In Figure 4, the full-line arrows indicate the direction of the water and the broken-line arrows, the course of the heat and products of combustion.

15 What I claim and desire to secure by Letters Patent is:

1. A boiler composed of a cylindrical lower section having an annular water-jacket around a combustion-space, a cylindrical upper section,

20 having an annular water jacket, inclusive of a steam-space and having a smoke-outlet in connection with the space inside the jacket, and a middle-section having a segmental annular water-jacket interconnected with the jackets of

25 the other sections, the spaces inside the jackets of the middle and upper sections providing flues for the passage of heat and products of combustion from the combustion space to the smoke-outlet, the three sections being horizontal.

30 2. A boiler composed of a cylindrical lower section having an annular water-jacket around a combustion space, a cylindrical upper section, having an annular water jacket, inclusive of a steam-space and having a smoke-outlet in con-

35 nection with the space inside the jacket, and a middle-section having a segmental annular water-jacket interconnected with the jackets of the other sections, the spaces inside the jackets of the middle and upper sections providing flues

40 for the passage of heat and products of combustion from the combustion space to the smoke-outlet, which have openings at the ends of the boiler, and doors closing the openings, the three sections being horizontal.

45 3. A boiler composed of a cylindrical lower section having an annular water-jacket around a combustion space, a cylindrical upper section, having an annular water-jacket, inclusive of a steam-space and having a smoke-outlet in con-

50 nection with the space inside the jacket, and a middle-section having a segmental annular water-jacket interconnected with the jackets of the other sections, the spaces inside the jackets of the middle and upper sections providing flues

55 for the passage of heat and products of combustion from the combustion space to the smoke-outlet, the flues and the combustion-space having openings at the ends of the boiler, and doors closing the openings, the three sections being horizontal.

60 4. A boiler composed of a cylindrical lower section having an annular water-jacket around a combustion space, a cylindrical upper section, having an annular water jacket, inclusive of a steam-space and having a smoke-outlet in con-

65 nection with the space inside the jacket, and a middle-section having a segmental annular water-jacket interconnected with the jackets of the other sections, a lengthwise extending neck connecting the jackets of the upper and lower sections, a neck connecting the jackets of the middle and upper sections, the spaces between

the jackets of the middle and upper sections and the necks, providing flues for the passage of heat and products of combustion from the combustion space to the smoke outlet, the three sections being horizontal.

5. A boiler composed of a cylindrical lower section having an annular water-jacket around a combustion space, a cylindrical upper section, having an annular water jacket, inclusive of a steam-space and having a smoke outlet in connection with the space inside the jacket, and a middle-section having a segmental annular water-jacket interconnected with the jackets of the other sections, a lengthwise extending neck connecting the jackets of the upper and lower sections, a neck connecting the jackets of the middle and upper sections, the spaces between the jackets of the middle and upper sections and the necks, providing flues for the passage of heat and products of combustion, and the jackets and the necks having ends distanced from the front and rear walls of the boiler, to connect the flues in a zig-zag course between the combustion space and the smoke outlet, the three sections being horizontal.

80 6. A boiler comprising a cylindrical section having a water jacket around a combustion space, a section having a water jacket and a steam-space, and a section having a water jacket intercommunicating with the water jackets of the other sections, in intersecting relation to the jacket of one of said sections, the spaces of the sections bounded by their jackets being closed at the ends of the sections and intercommunicating at opposed ends to provide a continuous flue for the passage of heat and products of combustion from the combustion space to a point of escape.

85 7. A boiler comprising a section having a water jacket around a combustion space, a section having a water jacket and a steam-space, and a middle section having segmental water jackets intercommunicating with the water jackets of the other sections, and a connection between the jackets of the first and second mentioned sections

90 100 intermediate of the jackets of the middle section, the spaces of the sections bounded by their jackets being closed at the ends of the sections and intercommunicating at opposed ends to provide a continuous flue for the passage of heat and products of combustion from the combustion space to a point of escape.

105 8. A boiler comprising a cylindrical section having a water jacket around a combustion space, a section having a water jacket and a steam-space, and a section having a water jacket intercommunicating with the water jackets of the other sections, in intersecting relation to the jacket of one of said sections, a connection between the jackets of the first and second mentioned sections

110 intermediate of the jackets of the middle section, and a connection between the middle section and the first mentioned jacket, substantially in line with the first connection, the spaces of the sections bounded by their jackets being closed at the ends of the sections and intercommunicating at opposed ends to provide a continuous flue for the passage of heat and products of combustion from the combustion space to a point of escape.

115 9. A boiler comprising a cylindrical section having a water jacket around a combustion space, a section having a water jacket and a steam-space, and a section having a water jacket intercommunicating with the water jackets of the other sections, in intersecting relation to the jacket of one of said sections, a connection between the jackets of the first and second mentioned sections

120 intermediate of the jackets of the middle section, and a connection between the middle section and the first mentioned jacket, substantially in line with the first connection, the spaces of the sections bounded by their jackets being closed at the ends of the sections and intercommunicating at opposed ends to provide a continuous flue for the passage of heat and products of combustion from the combustion space to a point of escape.

DOMONICK F. VALLERO.
